UNITED STATES PATENT OFFICE

154,996

DESIGN FOR AN AUTOMOTIVE INTAKE MANIFOLD

Max H. Ellis, Huntington Park, Calif.

Application March 29, 1947, Serial No. 138,028

Term of patent 14 years

(Cl. D14—6)

To all whom it may concern:

Be it known that I, Max H. Ellis, a citizen of the United States of America, residing in the city of Huntington Park, in the county of Los Angeles, State of California, have invented a new, original, and ornamental Design for an Automotive Intake Manifold, of which the following is a specification, reference being had to the accompanying drawing, forming a part thereof.

The characteristic features of my design reside in the portions shown by means of full lines in the drawing.

I claim:

The ornamental design for an automotive intake manifold, as shown and described.

MAX H. ELLIS.
